UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF WISCONSIN

LOCK

Application filed April 9, 1931. Serial No. 528,823.

This invention relates to certain new and useful improvements in locks and refers more particularly to what is generally termed a removable cylinder lock of the general type illustrated in my copending application Serial No. 390,737 wherein an operating key is utilized to disable the limiting means and permit further rotation of the cylinder to a point where the retaining means therefor is rendered inoperative.

One objection encountered in connection with removable lock cylinders is the inability to provide ample protection in the form of an armor and this invention has as an object the provision of a removable lock cylinder which has its exposed or outer portion thoroughly armored.

Another object of this invention resides in the provision of an improved lock of the character described wherein an assembling hood or cap member extends over the exposed end of the lock cylinder and the outer end portion of the lock cylinder mounting head and has means for maintaining the cylinder assembled with the mounting head, the lock cylinder and the hood being readily removable from the mounting head with the aid of a properly designed key.

Another object of this invention is to provide a lock structure of the character described in which a protecting cap secured over the outer end of the lock cylinder and mounting head not only releasably retains the lock cylinder in the mounting head, but also positively holds the mounting head against disassembly from its casing or other support when the lock is in locked position.

In this connection it is a further object of this invention to provide cooperating means carried by the mounting head, the cap, and the receiving casing or other support which, when in predetermined relative positions, permits the mounting head and the entire structure carried thereby to be removed from the receiving casing.

A further object of this invention resides in the provision of means carried by the receiving casing, the mounting head, and the cap member so disposed with respect to each other that rotation of the lock to its unlocked

position places the same in positions at which the release of the mounting head and the lock cylinder carried thereby may be effected.

A still further object of this invention resides in the provision of cooperating means carried by the mounting head and the receiving casing or other support which is normally engaged to preclude relative rotation of these elements and which may be disengaged when the lock cylinder is in a predetermined relative position to permit these elements to be disengaged and the mounting head turned with respect to its receiving casing.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a perspective view of a lock assembly embodying my invention, the mounting head and cylinder being removed from the outer casing or tube which is partly broken away and in section to illustrate structural details;

Figure 2 is a view partly in longitudinal section and partly in side elevation taken through the lock assembly;

Figure 3 is a transverse, sectional view taken through Figure 2 on the plane of the line 3—3;

Figure 4 is a transverse sectional view taken through Figure 2 on the plane of the line 4—4;

Figure 5 is a top elevational view of the lock assembly with parts broken away and in section, said view being taken on the plane of line 5—5 of Figure 4;

Figure 6 is a perspective view of the mounting head, the lock cylinder and the cap shown

separated and in their proper order of assembly; and

Figure 7 is a fragmentary, bottom plan view of the outer end portion of the lock cylinder.

Referring now more particularly to the accompanying drawings, in which like numerals designate like parts the numeral 10 designates the mounting head of a lock structure embodying my invention. A longitudinal bore 11 in the mounting head mounts a lock cylinder 12, which is provided with a plurality of conventional locking tumblers 13 yieldably urged to extend one end into

one of a pair of diametrically opposite longitudinal tumbler receiving grooves 14 formed in the mounting head in communication with its bore 11. As is customary the tumblers 13 are adapted to be retracted entirely within 20 the lock cylinder by a proper key 15 inserted into a key receiving opening 16 in the cylinder to free the cylinder for rotation.

At its outer end, the lock cylinder has an enlarged annular flange 17, the inner wall 25 18 of which abuts the outer face 19 of the mounting head and limits longitudinal movement of the lock cylinder into the mounting head, and outward movement of the lock cylinder is prevented by an armored cap 20 releasably secured over the outer end of the mounting head in a manner to be later described.

The cap 20 encloses the entire outer end of the lock cylinder and mounting head and being formed of hardened metal, forms a protecting housing therefor and resists destruction of the lock.

As best shown in Figure 6, the cap 20 is an open ended substantially cup shaped structure with its bottom formed with an outwardly extending central portion or depression 21, the internal diameter of which is substantially that of the enlarged flange 17 on the lock cylinder to snugly receive the same and 40 the inside diameter of the larger portion of the cap is such as to snugly receive the outer end 22 of the mounting head which is reduced in diameter so that the outer peripheral surface of the cap is substantially flush with 45 the major portion of the mounting head when these elements are assembled.

To hold the cap against removal from the mounting head, its inner open end portion is provided with a plurality of circumferentially spaced depressions or lugs 23 which are normally received in an annular channel 24 in the reduced outer end portion 22 of the mounting head. These depressions 23 are engageable into the annular groove through a plurality of entrance grooves or recesses 25 extended across the flange 26 between the outer face 19 of the mounting head and its groove 24, the entrance recesses being circumferentially arranged so as to align with the depression when the cap is in a predetermined relation

to the position of rotation with respect to the mounting head.

Rotation of the cap with respect to the mounting head to align the depressions with their respective outlet grooves or recesses 25 70 is, however, possible only under certain conditions to be later described, and never takes place during the normal operation of the lock.

As in all locks of this type, the lock cylinder has a predetermined degree of rotation and in the present instance, rotation is normally limited to 90 degrees and the limits of rotation are defined by abutments carried by the lock cylinder outer enlarged head 17 80 and the adjacent portion of the mounting head.

As best shown in Figure 6, the mounting head has a segment-like projection 27 extending outwardly from its outer end 19, the ends 28 and 29 of which cooperate with lock cylinder carried abutments to define the limits of rotation of the lock cylinder. It is noted that the end 28 of the segment-like projection 27 is in line with and forms a continuation 90 of one wall of one of the tumbler receiving grooves 14.

The lock cylinder carried abutments are formed by stepping its annular flange outwardly from its rear portion as at 30 which leaves a segment-like projection 31 which, when the cylinder is assembled with the mounting head, is in the plane of the segment-like projection 27 so that its ends 32 and 33 are engageable with the extremities 28 and 29 of the mounting head projection. The lock cylinder abutment provided by the end 32 of the segment-like projection 31 is engageable with the extremity 29 of the projection 27 to limit rotation of the lock cylinder from locked to unlocked position, and it is noted that when these abutments engage, the cylinder is turned 90 degrees with respect to its position illustrated in Figures 2, 4, and 5, and the axis of the tumblers is aligned with a third longitudinal tumbler receiving groove 34 to permit the key to be withdrawn.

The locked position of the lock cylinder is defined by the engagement of a movably mounted locking lug 35 on the lock cylinder with the extremity 28 of the mounting head projection 27. The locking lug 35 is carried by the free end of a flat spring member 36 disposed in a segmental recess 37 in the lock cylinder flange 17 with its extreme end portion opposite the lug 35 securely held as at 38 (see Figure 7). The outer end portion of the flat spring member by which the locking lug 35 is carried is thus free to move parallel with the lock cylinder axis, in the segmental recess 37 and the resiliency of the spring member normally maintains the locking lug in a position within the segmental recess 37 out of alignment with the segmental projection 27 on the mounting head.

The regular key 14, however, has a shoulder 39 which engages the free end portion of the spring member as best shown in Figure 2 and moves the locking lug 35 into the path 5 of the mounting member abutment 28 as the key is inserted so that during normal operation, the locking lug 35 is always moved to its operative position and engages the abutment 28 to limit movement of the lock cylinder in 10 locked position.

The cap member 20 has a key receiving opening 40 in its outer closed end to align with the key receiving slot 16 in the lock cylinder and an instruck tang 41 on the outer 15 closed wall of the cap is engageable in the key receiving slot 16 to hold the cap against relative rotation on the lock cylinder so that the cap turns with the lock cylinder. As best shown in Figure 4, in which the lock cylinder is in its locked position, the cap 20 is so located on the lock cylinder that its depressions 23 do not align with their respective outlet grooves 25 during the normal operation 20 of the lock so that accidental detachment 25 of the lock cylinder from the mounting head is impossible. Alignment of the depressions 23 with their respective outlet recesses 25 takes place only when the lock cylinder and cap are turned beyond the normal locked position 30 of the cylinder and to permit such rotation a special key is necessary. In this special key the shoulder 39 is either entirely omitted or is placed outwardly sufficiently far so as not to move the locking lug 35 to its 35 operative position.

As the special key does not move the locking lug 35 to operative position, it is thus possible to turn the lock cylinder beyond its normal locked position until the abutment 33 formed by one end of the segment-like projection on the lock cylinder engages the mounting head abutment 28. Engagement of these abutments aligns the cap member depressions 23 with their respective outlet grooves 25 and permits the cap and consequently the locking cylinder to be detached from the mounting head.

The lock structure so far described may be applied to any desired use, and in the present instance, it is shown as directly controlling a switch mechanism designated generally by the letter "S" which is mounted within an outer casing or supporting element 42. This switch structure consists of a pair of spaced stationary contacts 43 carried by a mounting panel 44 fixed in the receiving casing 42 and a movable contactor 45 having contacts engageable with the stationary contacts 43 to bridge the same. The contactor 45 is non-rotatably connected with a disc 47 of the insulating material which in turn is drivingly connected with the inner end 50 of the lock cylinder through a spider like driver 48 having apertures adapted to re-

ceive lugs 49 extended from the inner end of the lock cylinder.

An expansive spring 50 confined between the spider like driver and the disc 47 yieldably urges the contactor 45 toward the channel 44 and tends to push the mounting head outwardly of the receiving casing 42. The mounting head, however, is restrained against longitudinal movement in the receiving casing by the engagement of a radial tang 51 extended inwardly from the casing and received in a recess 52 in the mounting head. The recess 52 opens into the annular channel 24 so that during engagement or disengagement of the tang from the recess the tang must move into the channel 24. However, when the cylinder is in its locked position the inner end of the cap 20 which covers the channel 24, closes the recess 52 and prevents disengagement of the tang from the recess to positively preclude disassembly of the mounting head from the casing.

To permit the tang to be disengaged from its recess, the inner end of the cap 20 is partially cut away to provide a gate 53, but this gate is so located as to necessitate rotation of the lock cylinder to unlocked position so that the use of a key is required to effect disassembly. When the cylinder is in unlocked position, the cap 20 is so disposed with respect to the mounting head that the gate 53 aligns with the recess 52 and a longitudinal groove 54 in the outer surface of the mounting head so that the groove 54 together with the gate 53 forms in effect a bayonet slot through which the tang 51 may be passed to permit the removal or insertion of the mounting head into the outer casing.

During normal operation of the lock accidental disassembly is prevented by a screw passed through an opening 55 in the casing and threaded into an opening 56 in the mounting head, thus when it is desired to disassemble the mechanism it is necessary to remove the screw. After removal of the screw, inward pressure is exerted on the outer end of the lock cylinder or the key, moving the entire structure assembled within the casing inwardly against the action of the spring 50 to disengage the radial tang from the mounting head recess and align the same with the gate in the cap. The mounting head then may be turned to align the groove 54 with the tang and permit relative axial movement between the mounting head and the casing. It is noted that inasmuch as the abutments 32 and 29 of the lock cylinder and mounting head respectively are engaged when the lock cylinder is in its unlocked position it is possible to employ the key to impart rotation to the mounting head to effect alignment of the groove 54 with the tang 51.

From the foregoing description taken in connection with the accompanying draw-

ings, it will be readily apparent to those skilled in the art to which an invention of the character described appertains, that I provide novel means for removably securing a lock cylinder in its mounting head and for releasably maintaining the mounting head and lock cylinder, assembled with a supporting element, and in which the means for securing the elements assembled also serves as an armor for the outer exposed end of the lock structure to protect the same against destruction.

I claim:

1. In a lock structure including a mounting head, a lock cylinder and a supporting element in which the assembled mounting head and cylinder is received, single means for removably securing the cylinder in the mounting head and for positively preventing disassembly of the mounting head from the supporting element when the lock cylinder is in locked position.

2. In a lock structure including a mounting head, a lock cylinder and a supporting element adapted to receive the assembled mounting head and lock cylinder, a protecting element secured over the lock cylinder and mounting head, and means whereby said protecting element removably secures the lock cylinder in the mounting head and positively precludes detachment of the mounting head from the supporting element when the lock cylinder is in its locked position.

3. In a lock structure including a mounting head, a lock cylinder and a supporting element adapted to receive the assembled mounting head and lock cylinder, a single element associated with the mounting head, lock cylinder and supporting element and normally preventing disassembly of said elements, and means whereby movement of said element to different predetermined positions, which movements require the use of a key, enables the lock cylinder to be removed from the mounting head and the mounting head to be withdrawn from its supporting element.

4. In a lock structure including a mounting head and a key operable lock cylinder mounted therein, a protecting cap engaged over the lock cylinder and adjacent portion of the mounting head to removably retain the lock cylinder assembled with the mounting head, and means for securing the cap in operative position, said means being disabled by movement of the lock cylinder to a predetermined position.

5. In a lock structure including a mounting head having a lock cylinder mounted therein, a protecting cap engaged over one end portion of the lock cylinder and the adjacent portion of the mounting head for releasably securing the lock cylinder in the mounting head, and means whereby movement of the lock cylinder to a predetermined position enables the cap to be disengaged

from said elements to permit the lock cylinder to be withdrawn from the mounting head.

6. In a lock device of the character described including a mounting head and a lock cylinder mounted therein, a protecting element secured over the exposed portions of the lock cylinder and mounting head to hold the lock cylinder in the mounting head, and means whereby the protecting element may be removed to permit withdrawal of the lock cylinder from the mounting head upon movement of the lock cylinder and the protecting element to a predetermined position with respect to the mounting head by means of a key inserted into the lock cylinder.

7. In a lock structure including a mounting head, and a lock cylinder mounted therein, a protecting element secured over the exposed portion of the lock cylinder and the mounting head and releasably engaged with the mounting head to removably secure the lock cylinder in the mounting head, said protecting element being disengageable from the mounting head upon movement of the protecting element to a predetermined position with respect to the mounting head, and means whereby a special key is necessary to effect such movement.

8. In a lock structure including a mounting head and a lock cylinder mounted therein, a protecting cap secured over the exposed end portions of the lock cylinder and mounting head, interengaging means carried by the protecting cap and mounting head for securing the protecting cap on the mounting head to secure the lock cylinder in the mounting head, said interengaging means being disengageable upon movement of the protecting cap to a predetermined position with respect to the mounting head, and means whereby the protecting cap may be moved to said predetermined relative position upon the insertion of a special key into the lock cylinder.

9. In a lock structure of the character described including a lock cylinder and a mounting head, a protecting cap engaged over the exposed end portions of the lock cylinder and mounting head, interengaging means carried by the mounting head and said protecting cap to secure the lock cylinder in the mounting head, said interengaging means being disengageable upon movement of the protecting cap to a predetermined position with respect to the mounting head, and key controlled means for normally preventing movement of the cap to such position.

10. In a lock structure including a mounting head and a lock cylinder mounted therein, a protecting cap engaged over the exposed end portions of the lock cylinder and mounting head, an abutment carried by the protecting cap and engaged in a channel formed in the mounting head to secure the protecting cap against removal while permitting rotation thereof in the mounting head, said

mounting head having an outlet recess communicating with the channel through which the abutment may be passed to effect detachment of the cap from the mounting head, alignment of the cap carried abutment with the said outlet recess necessitating movement of the cap to a predetermined position with respect to the mounting head, and key controlled means for normally preventing movement of the cap to said predetermined position.

11. In a lock structure of the character described including a mounting head and lock cylinder movably mounted therein, a protecting member engaged over the exposed end of the lock cylinder and mounting head, abutments carried by the protecting cap and engaged in an annular channel in the mounting head to normally hold the cap against displacement from the mounting head and thus secure the lock cylinder in the mounting head, the mounting head having outlet recesses through which said abutments may be passed to enable the cap member to be engaged and disengaged from the mounting head, alignment of the cap member abutments with said outlet recesses necessitating movement of the cap and lock cylinder to a position beyond one of the normal limits of movement of the lock cylinder, and means whereby a special key enables movement of the lock cylinder and cap beyond said normal limit of movement to align the cap abutments with their respective outlet recesses.

12. In a lock structure of the character described including a mounting head and a supporting casing adapted to receive the mounting head, cooperating means carried by the supporting casing and the mounting head for releasably securing the mounting head in the supporting casing, said cooperating means being disengageable upon predetermined relative motion between the supporting casing and mounting head, and a protecting cap secured over the outer end of the mounting head and normally preventing such relative motion between the supporting casing and mounting head.

13. In a lock structure of the character described including a mounting head having a key actuated lock cylinder and a supporting casing adapted to receive the mounting head, cooperating means carried by the supporting casing and the mounting head for releasably securing the mounting head in the supporting casing, said cooperating means being disengageable to enable withdrawal of the mounting head from the receiving casing upon a predetermined relative motion between the mounting head and the supporting casing, and means movable with the key controlled lock cylinder for preventing such movement when the lock cylinder is moved by a proper key out of its locked position.

14. In a lock structure of the character de-

scribed including a mounting head having a key operable cylinder and a supporting casing adapted to receive the mounting head, cooperating means carried by the supporting casing and mounting head for detachably securing the mounting head assembled with the supporting casing, said cooperating means being disengageable upon a predetermined movement of the mounting head with respect to the supporting casing, a protecting cap secured over the outer end of the lock cylinder and the mounting head and movable with the lock cylinder, said protecting cap positively preventing movement of the mounting head with respect to the supporting casing when the lock cylinder is in its locked position, and means whereby movement of the lock cylinder and the protecting cap to predetermined positions by means of a proper key releases the mounting head for movement with respect to the supporting casing to enable the cooperating means to be disengaged.

15. In a lock structure of the character described including a mounting head having a key operable lock cylinder and a supporting casing adapted to receive the mounting head, cooperating means carried by the supporting casing and the mounting head for releasably securing the mounting head against detachment from the supporting casing, said cooperating means being disengageable upon a predetermined relative motion between the supporting casing and the mounting head, and a protecting cap connected with the mounting head to secure the lock cylinder therein, said protecting cap positively preventing relative motion between the mounting head and supporting casing except when the lock cylinder is moved by means of a proper key to a predetermined position.

16. In a lock structure of the character described including a mounting head member having a lock cylinder movable therein and a supporting member adapted to receive the mounting head member, a lug carried by one of said members and engageable in a recess in the other for detachably securing said members assembled, said lug being disengageable from said recess upon a predetermined relative movement of one member with respect to the other, and means carried by the mounting member and preventing such movement while the lock cylinder is in locked position.

17. In a lock structure of the character described, including a mounting head member having a key operable lock cylinder mounted therein and a supporting member adapted to receive the mounting head member, a lug carried by one member and engageable through a slot in said other member with a recess in said other member upon predetermined relative movements between said members, and means carried by the mounting

head member and movable with the lock cylinder for closing communication between said slot and recess except when the lock cylinder is moved out of its locked position by means of a key to prevent the passage of the lug to and from the recess.

18. In a lock structure of the character described including a mounting head having a key operable lock cylinder therein and a supporting casing adapted to receive the mounting head, means for detachably securing the mounting head assembled with the supporting casing, comprising a lug carried by the supporting casing and engageable in a recess in the mounting head, said mounting head having a longitudinal groove through which the lug may be passed to enable the same to be engaged with and disengaged from the mounting head recess, said groove and recess being circumferentially spaced whereby rotational movement of the mounting head with respect to the supporting casing is necessitated to align the lug with the recess during insertion of the mounting head and to align the head with the groove during removal of the mounting head, and a protecting cap carried by the mounting head and normally closing the recess to prevent detachment of the lug from the recess.

19. In a lock structure of the character described including a mounting head having a key operable cylinder therein and a supporting casing adapted to receive the mounting head, means for detachably securing the mounting head assembled with the supporting casing, comprising a lug carried by the supporting casing and engageable in a recess in the mounting head, said mounting head having a longitudinal groove through which the lug may be passed to enable the same to be engaged with and disengaged from the mounting head recess, said groove and recess being circumferentially spaced whereby rotational movement of the mounting head with respect to the supporting casing is necessitated to align the lug with the recess during insertion of the mounting head and to align the groove with the lug during removal of the mounting head, and a protecting cap carried by the mounting head and movable with the lock cylinder, said protecting cap normally closing the entrance to the recess and having a gate adapted to communicate the recess with the longitudinal groove upon movement of the lock cylinder and the cap by means of a proper key to a predetermined position.

In testimony whereof, I hereunto affix my signature.

EDWARD N. JACOBI.
